UNITED STATES PATENT OFFICE.

ANTHONY ZAREMBA, OF CHICAGO, ILLINOIS.

NOTEBOOK CLIP.

Application filed August 1, 1925. Serial No. 47,601.

To all whom it may concern:

Be it known that I, ANTHONY ZAREMBA, a citizen of the United States, and a resident of Chicago, in the county of Cook and State 5 of Illinois, have invented a new and useful Improvement in Notebook Clips, of which the following is a full, clear, and exact description.

My invention relates to improvements in 10 note book clips, and it consists in the combinations, constructions, and arrangements herein described and claimed.

An object of my invention is to provide a 15 note book clip of the character described which may be used for securing a note book from unintentional dislodgment from the pocket of the user.

A further object of my invention is to provide a note book clip of the character described in which means is provided for gripping the note book at the top or at the side thereof so as to accommodate the device to books of various proportions and sizes with 20 respect to the size of the pocket of the user.

A further object of my invention is to provide a note book clip of the character described consisting of but three parts, and which is extremely simple in construction 25 as well as cheap to manufacture.

Other objects and advantages will appear 30 in the following specification, and the novel features of the invention will be particularly pointed out in the appended claim.

My invention is illustrated in the accompanying drawings, forming part of this application, in which

Figure 1 is a front elevation of an embodiment of my invention,

Figure 2 is a view along the line 2—2 of 40 Figure 1,

Figure 3 is a sectional view along the line 3—3 of Figure 1, and

Figure 4 is a top plan view of the note 45 book clip secured to the side of a note book.

In carrying out my invention I make use 50 of the ordinary type of note book having covers 1 and leaves 2, all of which are bound together in any well known manner.

My improved note book clip consists of a 55 body member 3 of resilient metal having a portion 4 thereof bent rearwardly parallel with the body member so as to form a pair of parallel gripping surfaces 5 between which one of the covers 1 of the book may be secured. When the gripping portions 5 are

employed, the clip is secured to the front edge of the cover, as shown in Figure 4.

The portion 4 has a part 6 thereof bent rearwardly and downwardly parallel therewith so as to form parallel and adjacent 60 gripping portions 7 between which the cover 1 of the book may be engaged by placing the clip over the top edge of the cover as shown in Figures 1 and 2.

The body member 3 has a pair of forwardly extending parallel ears 8 formed integral therewith upon which a spring actuated gripping finger 9 is pivotally mounted by means of ears 10 formed integral with the finger 9 which have stud shafts 11 at the 70 outermost ends thereof projected through openings in the ears 8.

A spring 12 bent at 13 at a point intermediate its length has its opposite ends in engagement with the body member 3 and the 75 upper end of the finger 9. It will be noted that the finger 9 is turned over at 14 to more readily facilitate the engagement of the spring 12 therewith.

The cross sectional contour of the finger 80 9 is curved as shown in Figure 3, and the finger has a pair of rounded gripping portions 15 at the lowermost end thereof which are bent inwardly in a plane transverse to the cover 1 of the book.

From the foregoing description of the various parts of the device, the operation thereof may be readily understood. If the book is one of ordinary height which may be readily placed within the pocket of the 90 user and does not extend for any appreciable distance above the top of the pocket, the gripping surfaces 7 are engaged with the outer cover 1 of the book, and the gripping finger 9 is permitted to engage by means of 95 the spring 12 with the pocket as shown in Figures 1 and 2.

If the book is an exceedingly tall one, it will be necessary to engage the cover 1 with the gripping surfaces 5 at the outer edge 100 of the book, as shown in Figure 4, whereupon the finger 9 is employed in the same manner as shown in Figure 1.

In order to more readily facilitate the engagement of the cover 1 with the gripping surfaces 5 or 7 of the device, one corner of the parts 3 and 6, respectively, is bent outwardly as shown at 16 and 17, respectively. Without these slightly bent portions there would be a tendency for the adjacent parts 110

of the device to dig into the cover 1 as the device was inserted in place upon the cover.

I claim:

The combination with a note book having a cover, of a spring actuated gripping member, a body member associated with the gripping finger having an overlapped portion arranged for engaging with the horizontal

edge of the note book when the gripping finger is in a vertical position, and having a ¹⁰ further folded portion arranged for engagement with the vertical edge of the note book when the gripping finger is in a vertical position.

ANTHONY ZAREMBA.
